United States Patent Office

Des. 216,844
Patented Mar. 10, 1970

216,844

WRITING INSTRUMENT

Shoji Shimada, Tokyo, Japan, assignor to Iwasaki Kinzoku Kogyo Company, Limited, Tokyo, Japan, a corporation of Japan

Filed Dec. 30, 1968, Ser. No. 15,152

Claims priority, application Japan Dec. 21, 1968

Term of patent 14 years

Int. Cl. D19—06

U.S. Cl. D74—17

FIG. 1

FIG. 3

FIG. 4

FIG. 2

FIG. 1 is a perspective view of a writing instrument showing my new design as it appears with the point in projected position;

FIG. 2 is a front elevational view thereof as it appears with the point in retracted position;

FIG. 3 is an enlarged top plan view of FIG. 2; and

FIG. 4 is an enlarged bottom plan view of FIG. 2.

I claim:

The ornamental design for a writing instrument or similar article, substantially as shown and described.
